Marie L. Livingston, of New York, N.Y.
Letters Patent No. 1311, dated Sept. 4, 1860.

The schedule referred to in these Letters Patent and making part of the same.

To all whom it may concern:

Be it known that I, Marie L. Livingston, of the City of New York, in the State of New York, have originated, produced and made a new and original design for a composition in alto relief of a medallion bust of Washington Irving, and I do hereby declare that the following is an exact description of the same as far as it can be described.

The said medallion is of life size, and is a bust showing the face in three quarters projection - with the head and neck only in view.

A photograph taken from the medallion is hereto attached and is to be taken or forming a description of the medallion and is a part of this description.

The negative and a copy of the photograph being deposited in the Patent Office.

What I claim as my invention, is a medallion alto relief likeness of said Washington Irving as designed and formed in the description herein contained.
